UNITED STATES PATENT OFFICE.

GEORGE M. BECHTEL, OF READING, PENNSYLVANIA.

SHUTTER-BOLT.

SPECIFICATION forming part of Letters Patent No. 291,023, dated January 1, 1884.

Application filed July 31, 1883. (Model.)

To all whom it may concern:

Be it known that I, GEORGE M. BECHTEL, a citizen of the United States, and a resident of the city of Reading, county of Berks, State of Pennsylvania, have invented a new and useful Improvement in Shutter-Bolts, of which the following is a specification.

This improvement relates to that class of shutter-bolts provided with means for the bowing of the same.

The object of the improvement is to combine with a shutter bolt or fastener an adjustable bowing and locking stop, and, in lieu of the shutter-rings usually attached below the bolt, to add to the same a fixed equivalent therefor, forming an integral portion of the bolt and keeper case.

The drawings herewith, forming a part of this specification, will enable an expert to construct the same according to my invention.

Like letters indicate like parts throughout the same.

Figure 1 is a front elevation of the shutter-bolt and keeper-plate as locked upon the shutter. Fig. 2 is a top plan of the same. Fig. 3 is a top view of the locking-bar. Fig. 4 is a side and end view of the same. Fig. 5 is a reverse or back elevation of the improved shutter-bolt. Fig. 6 is an end view of the keeper-plate, showing the shutter-pull.

A represents the bolt-plate; A', the bolt-case; A², a longitudinal slot for the shifter-button; A³, shutter-pull integral with the case and plate; A⁴, screw-holes; A⁵, enlargement and recess in case for head D² of locking-bar; A⁶, ledge for the retention of the locking-bar in a non-locking position; B, the bolt; B', the shifter-button; B², the bowing-hook; B³, locking-notches in the top edge of the bolt; C, the keeper-plate; C', the keeper; C², inclined plane; C³, shutter-pull integral with the keeper and plate; C⁴, screw-holes; C⁵, bowing-hook seat; D, locking-bar; D', retaining-clip; D², enlargement of bar; D³, abutting-stop; D⁴, shifting-head; D⁵, locking-stop.

The bolt-plate and keeper-plate are both so constructed and arranged that they may be molded in ordinary snap-flasks, and are cast complete, requiring no machine-fitting to receive the bolt and locking-bar. The bolt has

at one end the usual bowing-hook, the opposite end having on its upper edge a series of notches to receive the stop D⁵. It is drilled for and has riveted to it the shifter-button B'. The locking-bar stop D⁵, in its normal state, 55 rests upon the ledge A⁶ and slides freely in the case A' upon the bolt B. It is provided with a clip, D', to retain it upon the bolt edge, with an enlargement, D², to lock the bolt downward, and with an abutting-stop, D³, to prevent withdrawal from the case; a head, D⁴, for shifting, and a stop, D⁵, for locking the bolt by dropping into the notches B³ of the same. The shutter-pulls A³ C³, integral with the bolt and keeper plates, are convenient of 65 access, always ready for the insertion of the fingers, reduce the expense of the shutter-fittings, and save much annoyance in stormy and freezing weather in loosening rings—the usual appliances.

To assemble the bolt, case, and locking-bar, the locking-bar D is first inserted in the case A'. The bolt B is then put in place and the shifter-button riveted in, which thus secures both bolt and locking-bar movably within the 75 case.

To operate the device as a bower, the stop D⁵ is drawn back and rested upon the ledge A⁶, the hook B² is dropped in its seat C⁵, and the shutters opened to the desired extent. 80 The stop D⁵ is then removed from the ledge A⁶ and dropped into the notch B³ nearest the end of the case A'. At the same time the enlarged head D² is carried forward between the bolt B and the top edge of the front opening 85 in the case, and locks the bolt downward, so that while it remains in that position the hook B² cannot be released from its seat C⁵.

To lock the shutter, the stop is lifted out of the notch and carried rearward to its first position upon the ledge, the shutters are closed, and the bolt thrown forward to the full extent of its movement, in which position the last notch B³ of the bolt is just outside of the case A'. The locking-bar is again set forward and 95 the stop D⁵ dropped therein, which effectively locks both shutter and bolt, and, unless from the interior of the house, the bolt is burglar-proof. The hump A⁵ in the case is extended down the front inside of the case far enough 100

to clear the thickened head D² and its clip D³. The abutting-stop D⁴ limits the movement of the locking-bar and its stop rearward.

By the adoption of the locking-bar D, great freedom of the bolt-bar B is obtained, and yet when the shutters are either locked or bowed all annoyance from rattling by high winds is prevented thereby. When the locking-bar D is drawn rearward with its stop D⁴ upon the ledge A⁶, the bolt-bar B is relieved from all pressure; but when the lock-bar D is thrown forward toward the keeper-ease C it locks the bolt-bar B rigidly in place, whether the shutters are bowed or locked, and as long as this position of the locking-bar is maintained the lock can only be released from the interior of the building, and the shutters are burglar-proof.

Having shown the construction, application, and operation of my shutter-bolt, I desire to secure by Letters Patent the following claims thereon:

1. In combination with a shutter-bolt provided with the usual bolt and keeper case, a series of notches, B³, on the rear upper edge 25 of the bolt, and a locking-bar, D, with a stop, D³, adapted to seat therein, a ledge, A⁶, to support the stop when not engaged with the bolt, the bar thickened at its forward end to lock the bolt downward, the keeper-ease provided with an inclined plane, C², bowing seat

C³, and both keeper and bolt cases, and plates having shutter-pulls A³ and C³ cast integral therewith, substantially as shown, and for the purpose set forth.

2. A locking-bar, D, provided with a clip, 35 D³, a thickened head, D², abutting-stop D⁴, head D¹, and locking-stop D⁵, in combination with bolt-case A¹, keeper-ease C¹, and plates A² C², provided with shutter-pulls A³ C³, cast integral therewith, bowing seat C², bolt B, and 40 notches B³, whereby, when the bolt B is in either a locked or bowed position and the bar D thrown forward, the bolt B is rigidly locked downward in the keeper-ease C¹ or upon the bowing seat C², the withdrawal of the bar D, 45 with its foot D³ placed upon the ledge A⁶, releasing the bolt B and giving greater freedom of movement thereto, substantially as and for the purpose described.

3. As an improved construction of shutter-bolts, the shutter-pulls A³ and C³, as shown and described, cast integral with the bolt and keeper cases and plates thereof, whereby the shutter-fittings are made more compact and accessible, substantially as and for the purpose set forth.

GEORGE M. BECHTEL.
